ELEVATOR SYSTEM

Herman Frederick Krantz, Buenos Aires, Argentina, assignor to Otis Elevator Company, New York, N. Y., a corporation of New Jersey

Application June 29, 1934, Serial No. 733,073

10 Claims. (Cl. 187—29)

This invention relates to elevator systems, and particularly to elevator systems comprising a group of two or more elevators.

The invention is directed to elevator systems in which control switches, such as push buttons, are provided at the floors to control the stopping of the cars, the starting and stopping of the cars, or the giving of stopping signals to the cars. Such systems may also be provided with similar control switches in the cars.

In elevator installations comprising a group of two or more elevators each provided with an individual set of hall buttons for enabling an intending passenger at a floor to register his demand for elevator service upon each elevator car individually—as by pushing the appropriate hall button for the corresponding elevator car—conditions arise as a result of which unnecessary movements and stops on the part of one or more of the elevator cars may occur. One of such conditions arises when an intending passenger in a hall presses corresponding hall buttons at a floor for each of two or more elevator cars. Another of such conditions arises when an intending passenger in a hall demands service of one elevator at a time when another elevator car is already destined to stop at such floor, as for example, to let off a passenger in such other car.

The object of this invention is the elimination of unnecessary movements and stops by the elevator cars in an elevator installation where hall buttons are provided individual to each car.

One feature of the invention is the provision of a control for each of the elevator cars such that whenever a demand for service from the hall at any floor is registered for one elevator car, similar demands cannot be registered for any of the other elevator cars pending the response of the first car to such demand.

Another feature of the invention is the provision of a control for each of the elevator cars such that whenever one car is destined to stop at a floor in order to discharge a passenger, no demand for service from such floor may be registered for any of the other cars.

A third feature of the invention is the provision of a control which, in addition to having the foregoing features, is such that whenever one car is destined to stop at a floor—either as a result of a demand for service from such floor or to such floor—any other elevator car may stop to discharge passengers at such floor.

Other features and advantages will become apparent from the specification and the accompanying drawings.

The invention involves interconnecting the hall button circuits for the various elevator cars in the group in such a manner that while a hall call is registered for one of such cars, similar hall calls cannot be registered for any of the other of such cars. The invention also involves interconnecting the hall button circuits and the car button circuits for the various cars (when car buttons are provided therein) in such a manner that while a car button stop at any floor is destined to be made by one of such cars, hall calls from such floor cannot be registered for any of the other of such cars.

In the drawings:

Figure 1 is a schematic view of a group of two elevators to which the invention is particularly applicable;

Figure 2 is a simplified schematic diagram of part of the control circuits for each of two elevators, such as illustrated in Figure 1, embodying the invention;

Figure 3 is a schematic view of a portion of a group of two elevators to which the invention is also applicable; and

Figure 4 is a simplified schematic diagram of part of the circuits for each of two elevators, such as illustrated in Figure 3, embodying the invention.

Referring to Figure 1 of the drawings, the two elevator cars, car A and car B, are illustrated as serving four floors. Cab 10 of car A is supported by cables 11, which pass around hoisting sheave 12 and are connected to counterweight 13. Hoisting sheave 12 is driven by hoisting motor 14 and subject to the action of a spring-applied, electromagnetically-released brake 15. In a similar fashion, cab 60 of car B is supported by cables 61, which pass around hoisting sheave 62 and are connected to counterweight 63. Hoisting sheave 62 is driven by hoisting motor 64 and subject to the action of a spring-applied, electromagnetically-released brake 65. Car A is shown as provided with a selector machine 7 driven in accordance with the motion of car A by means of a chain 8 connecting cab 10 and counterweight 13 and passing over sprocket 9 of the selector machine. Car B is provided with a similar selector machine 57 driven in a similar fashion by chain 58 and sprocket 59.

At each of the floors served by car A is provided a hall button for such car, these hall buttons for car A being designated 101, 201, 301 and 401. Within cab 10 of car A is provided a car button for each of the floors served by car A, these car buttons being designated 103, 55

203, 303 and 403. At each of these same floors a hall button is provided for car B, these hall buttons for car B being designated 102, 202, 302 and 402. Within cab 60 of car B is provided a 5 car button for each of these same floors, these car buttons for car B being designated 104, 204, 304 and 404. Hall buttons 101, 201, 301 and 401 for car A are provided to register demands of intending passengers in the halls for service by 10 car A. Hall buttons 102, 202, 302 and 402 for car B are provided to register demands of intending passengers in the halls for service by car B.

Referring to Figure 2, the invention is therein 15 illustrated as embodied in the control circuits for two single automatic push button elevators, each serving the same four floors and each provided with an individual set of hall buttons, as 20 illustrated in Figure 1. In this figure, the coils and contacts of the electromagnetic switches are separated in the interest of simplicity of circuits. For convenience in understanding the diagram, 25 however, each coil is associated with the contacts which it operates by means of a dot-and-dash line.

Switches 131, 230, 231, 330, 331 and 430 are 30 switches of selector machine 7 mechanically actuated in accordance with the motion of car A. Switches 141, 240, 241, 340, 341 and 440 are 35 switches of selector machine 57 mechanically actuated in accordance with the motion of car B.

The various electromagnetic switches employed 35 in the diagram chosen to illustrate the principles of the invention are designated as follows:

UA—Up direction switch, car A
DA—Down direction switch, car A
1FA—Floor relay, 1st floor, car A
2FA—Floor relay, 2nd floor, car A
3FA—Floor relay, 3rd floor, car A
4FA—Floor relay, 4th floor, car A
WA—Car button switch, car A
YA—Hall breaking switch, car A
ZA—Hall time limit relay, car A
UB—Up direction switch, car B
DB—Down direction switch, car B
1FB—Floor relay, 1st floor, car B
2FB—Floor relay, 2nd floor, car B
3FB—Floor relay, 3rd floor, car B
4FB—Floor relay, 4th floor, car B
WB—Car button switch, car B
YB—Hall breaking switch, car B
ZB—Hall time limit relay, car B

The electromagnetic switches are shown in 55 their deenergized positions. The various elements of the control system are shown in the positions they occupy when both car A and car B, empty, are stationary at the first floor, with the car gate for each car in closed position, with all the hatchway doors in closed position, with the hatchway doors at the first floor unlocked, with all time intervals expired, and with the control circuits for each car disconnected from the power mains.

Let it be assumed that car A and car B are 60 made available for service by closing knife switches 16, 20, 66 and 70. Let it also be assumed that an intending passenger at the third floor pushes hall button 301 for car A. A circuit is thereby completed from the plus main, by way of knife switch 16, various safety devices (such as limit switches, overspeed governor, etc.) 65 represented by the square 30, movable platform contacts 31 controlled by the movable car plat-

form of car A (and also gate contacts 32 in parallel therewith since the car gate for car A is in closed position), retiring cam magnet 37, actuating coil 310 of the third floor floor relay 3FA, contacts 322 of relay 3FB, hall push button 301, 5 movable platform contacts 25 controlled by the movable car platform of car A, contacts 26 of hall time limit relay ZA, contacts 27 of hall breaking switch YA, contacts 34 of up direction switch UA, contacts 35 of down direction switch 10 DA, stop button 36, knife switch 20, to the minus main. Energization of retiring cam magnet 37 and of actuating coil 310 of the floor relay thereby results.

The energization of retiring cam magnet 37 15 withdraws retiring cam 38 on car A to effect the locking of the hatchway door at the first floor for car A, this locking action also completing the circuit through the hatchway door interlock contacts 106 for the first floor. The 20 energization of actuating coil 310 of floor relay 3FA causes the engagement of its contacts 311 and separation of its contacts 312. The separation of contacts 312 will be considered later. The engagement of contacts 311, together with 25 the completion of the circuit through hatchway door interlock contacts 106, establishes a holding circuit for actuating coil 310 and retiring cam magnet 37. This holding circuit is from the plus main, by way of knife switch 16, safety 30 devices 30, platform contacts 31, retiring cam magnet 37, actuating coil 310, contacts 311, third floor up selector switch 330, fourth floor selector switch 430, actuating coil 40 of up direction switch UA, contacts 41 of down direction switch 35 DA, first, second, third and fourth floor hatchway door interlock contacts 106, 206, 306 and 406, respectively, stop button 36, knife switch 20, to the minus main.

Actuating coil 40 of the up direction switch 40 UA being in the above described holding circuit, up direction switch UA thereupon operates to cause the engagement of its contacts 18, 44 and 46 and the separation of its contacts 34 and 42. The separation of contacts 34 prevents 45 the energization of any floor relay for car A by the subsequent operation of any hall or car push button for car A. As a consequence the intending passenger at the third floor has 50 obtained exclusive control of car A.

The engagement of contacts 18 completes a 55 circuit for actuating coil 17 of hall time limit relay ZA, which relay immediately operates to cause the separation of its contacts 26. The separation of contacts 26 is of no effect at this time, due to the 60 existing separation of contacts 34. The separation of contacts 42 of up direction switch UA prevents energization of actuating coil 43 of the down direction switch DA while up direction switch UA is operated.

The engagement of contacts 44 and 46 of up 65 direction switch UA results, through the intermediary of circuits and other apparatus for simplicity not shown, in the release of brake 15 and in the energization of hoisting motor 14 so as to move car A in the up direction.

Car A thereupon leaves the first floor and proceeds to the third floor. As the car leaves the first floor, first floor selector switch 131 closes to enable 70 the car to return to the first floor. As the car passes the second floor, the second floor up selector switch 230 opens and the second floor down selector switch 231 closes, in order to enable the car to return to the second floor. The operation of 75

these switches is of no effect under the assumed conditions of operation, as the first floor and second floor floor relays 1FA and 2FA are not energized.

5 As car A nears the third floor, third floor up selector switch 330 opens, thereby interrupting the holding circuit for retiring cam magnet 37, and actuating coils 310 and 40 of switches 3FA and UA, respectively. As actuating coil 310 deenergizes, 10 contacts 311 separate in preparation for a subsequent operation of relay 3FA. As actuating coil 40 deenergizes, up direction switch UA returns to its initial position, thereby interrupting, at contacts 44 and 46, the circuits for the elevator motor 15 and brake to cause the stopping of car A at the third floor. The deenergization of retiring cam magnet 37 results in the projection of retiring cam 38 and thus, in the unlocking of the third floor hatchway door. The separation of contacts 18, 20 incident to the return of up direction switch UA to its initial position, deenergizes actuating coil 17 of hall time limit relay ZA, but due to the dashpot or other equivalent device 28, contacts 26 of relay ZA do not reengage until after the expiration of a 25 definite period of time. As a consequence, during this period of time the hall buttons for car A are ineffective so as to afford the intending passenger at the third floor sufficient time to open the unlocked hatchway door at the third floor and 30 take possession of car A.

The operation just described assumes that, with car A and car B at the first floor and available for service, an intending passenger at the third floor pushes the third floor hall button 301 for 35 car A. As explained, car A thereupon proceeds to respond to such demand for service. However, let it be assumed that, instead of pushing the third floor hall button 301 for car A, the intending passenger pushes the third floor hall button 302 for 40 car B. A response to such demand for service is thereupon made by car B in a manner similar to that described for car A. This is outlined as follows:

The operation of third floor hall push button 45 302 completes an energizing circuit for the actuating coil 320 of third floor floor relay 3FB, and also for the retiring cam magnet 87. Upon the completion of the circuit through the first floor hatchway door interlock contacts 107 (resulting 50 from the withdrawal of retiring cam 88), a holding circuit is established for the floor relay 3FB and the retiring cam magnet 87, this holding circuit including actuating coil 30 of up direction switch UB. The resulting operation of up direction switch UB starts car B in the up direction. 55 When car B nears the third floor, the third floor up selector switch 340 opens, thereby dropping out up direction switch UB, floor relay 3FB and retiring cam magnet 87 to bring car B stationary at the third floor with its third floor hatchway door unlocked. The intending passenger at the third floor may then take possession of car B, sufficient time, after the disengagement of contacts 60 68 of up direction switch UB, being afforded for this by the time delay in the reengagement of contacts 76 of relay ZB.

From the foregoing, it is believed clear that, with both car A and car B available for service, in the event an intending passenger in a hall pushes the appropriate hall button for one car (which may be either car), the car that responds to such demand for service is the car for which the intending passenger has pushed the hall button.

In the event the intending passenger in a hall 75 pushes the hall button for car A and for car B,

it is provided, in accordance with this invention, that only one of such cars responds thereto. To illustrate, let it be assumed, as in the previous assumptions, that car A and car B are at the first floor and available for service. Let it also be assumed that the intending passenger at the third floor pushes both the third floor hall button 301 for car A and the third floor hall button 302 for car B, the hall button for car A being pushed first.

The operation of the hall button 301 for car 10 A immediately energizes, in the manner previously explained, the third floor floor relay, 3FA, for car A. Incident to the resulting actuation of relay 3FA is the separation of its contacts 312. Contacts 312 are positioned in the third floor 15 hall button circuit for car B, and as a result of their separation, the operation of the third floor hall button 302 for car B is ineffective to complete a circuit for the third floor floor relay, 3FB, for car B. The intending passenger's push of 20 the third floor hall button 302 for car B is therefore ineffective to cause car B to respond to his demand for service. Car A, however, responds to such intending passenger's demand for service, the response being the same as though only the 25 third floor hall button 301 had been pushed, which operation has previously been disclosed in detail. It is believed sufficient to note that after the initial energization of actuating coil 310 of floor relay 3FA by the operation of hall 30 button 301, a holding circuit is established which maintains such actuating coil energized—and thus maintains contacts 312 separated—until car A stops at the third floor. At no time, therefore, after the initial operation of the third floor hall 35 button 301 for car A, until car A arrives at the third floor in response to such demand for service, is the third floor hall button 302 for car B effective to register demand for service by car B. Car B hall buttons 102, 202 and 402 for each 40 of the floors other than the third, however, remain effective so that immediate service may be provided by car B for an intending passenger at any of such floors while car A is providing service for the intending passenger at the third floor. 45

In the event the intending passenger at the third floor pushes hall button 302 for car B slightly prior to pushing hall button 301 for car A, car B responds to such intending passenger's demand for service, and car A remains stationary, 50 due to the disabling of hall button 301 for car A by the separation of contacts 322 of floor relay 3FB. In addition, third floor hall button 301 for car A remains disabled until car B stops at the third floor. 55

The interconnection of the hall button circuits for cars A and B thus, under the conditions last assumed, prevents one of the cars making an unnecessary trip, and holds such one car in readiness to provide immediate service for some 60 other intending passenger.

The description of the operation of the elevator system of Figure 2 when taking in consideration car button operations as well as hall button operations, for convenience assumes, as before, that both car A and car B are stationary at the first floor with their control circuits connected to the power mains, with the cars empty, with all the hatchway doors in closed position, with the hatchway doors at the first floor unlocked, and all the time intervals expired. Let it also be assumed that a person at the first floor, desiring to go to the third floor, opens the first floor hatchway door for car A, enters car A, closes the first floor hatchway door and also the car 70 75

gate for car A, and pushes the third floor car button 303 for car A.

When such person, in entering car A, steps upon the car platform, movable platform contacts 31 and 25 separate. The separation of platform contacts 31 requires that the car gate be closed (so that gate contacts 32 are in engagement) before car A may be started. The separation of platform contacts 25 breaks the circuit 10 for all the hall buttons for car A so that the car is under the exclusive control of the passenger therein, without interference from the halls.

The operation of third floor car button 303 completes a circuit from the plus main, by way 15 of knife switch 16, safety devices 30, car gate contacts 32, retiring cam magnet 37, actuating coil 310 of the third floor floor relay 3FA, car push button 303, actuating coil 33 of car button switch WA, contacts 34 of up direction switch 20 UA, contacts 35 of down direction switch DA, stop button 36, knife switch 29, to the minus main. Energization of retiring cam magnet 37 and of actuating coils 310 and 33 thereby results.

25 The energization of retiring cam magnet 37 withdraws retiring cam 38 on car A to effect the locking of the first floor hatchway door for car A, this locking action also completing the circuit through the hatchway door interlock contacts 30 106 for the first floor. The energization of actuating coil 33 of car button switch WA causes the engagement of its contacts 23 to complete a circuit for actuating coil 21 of hall breaking switch YA. The resulting operation of contacts 35 27 of switch YA breaks the circuits for all the hall buttons for car A while the resulting engagement of contacts 22 of switch YA renders switch YA self-holding, subject only to the car gate contacts 32 and the safety devices. The energization of actuating coil 310 of floor relay 3FA causes the engagement of its contacts 311 and the separation of its contacts 312. The separation of contacts 312 will be considered later. The engagement of contacts 311, together with the 40 completion of the circuit through the hatchway door interlock contacts 106, establishes a holding circuit, previously described, for actuating coil 310 and retiring cam magnet 37, this holding circuit including actuating coil 40 of up direction switch UA. Car A is therefore started in the up direction. When car A nears the third floor, the third floor up selector switch 330 opens, thereby dropping out up direction switch UA, floor relay 3FA and retiring cam magnet 37 to 45 bring car A stationary at the third floor with its third floor hatchway door unlocked. The passenger in car A may then leave the car by opening the car gate and the hatchway door.

Let it be assumed that the person at the first 60 floor, desiring to go to the third floor, enters car B instead of entering car A as last assumed. It is believed clear that upon closing the car gate and the first floor hatchway door for car B and pushing the third floor car button 304 for car B, such person is taken by car B to the third floor in a manner analogous to that described for car A.

Let it now be assumed that car A and car B are stationary at the first floor and available for service, and that a passenger enters car A at the first 70 floor, closes the car gate and hatchway door and pushes the third floor car button 303. Car A thereupon proceeds to the third floor in the manner previously described. Let it also be assumed that, after the car button 303 is operated, and 75 prior to the arrival of car A at the third floor, an

intending passenger at the third floor, desiring elevator service, pushes the third floor hall button 301 for car A and also the third floor hall button 302 for car B.

In the type of control illustrated in Figure 2— 5 known as single automatic push button control—it is provided that the passenger in car A has exclusive control of car A. As a consequence, the operation of hall button 301 for car A, under the assumed conditions, is of no effect. Specifically, 10 this ineffectiveness is due to the separation of platform contacts 25, of contacts 26 of switch ZA, of contacts 27 of switch YA, and of contacts 34 of switch UA. Car A is, however, destined to stop at the third floor by virtue of the prior operation 15 of car button 303, so the ineffectiveness of hall button 301 is of little significance.

With respect to the operation of third floor hall button 302 for car B under the assumed conditions, it is provided, in accordance with this invention, that such operation of the hall button is ineffective. Such rendering ineffective of the third floor hall button 302 for car B is in the interest of preventing car B, under the circumstances, making an unnecessary trip, for car A is 25 already destined to stop at the third floor. It is also in the interest of holding car B ready to provide immediate service for an intending passenger at any floor other than the third floor while car A is on its way to provide service to and from 30 the third floor. The rendering ineffective of the third floor hall button 302 for car B while car A is destined to stop at the third floor as a result of the prior operation of the third floor car button 303 for car A, is accomplished by the separation 35 of contacts 312 of the floor relay 3FA. This relay is actuated, as previously explained, upon the operation of the third floor car button 303 for car A and is maintained actuated while car A is proceeding to the third floor. The contacts 312 of relay 3FA are positioned in the third floor hall button circuit for car B, and by their separation prevent third floor hall button 302 for car B from completing a circuit to register a demand for service by car B.

Although, under the conditions assumed, the third floor hall button 302 for car B is rendered ineffective, it is to be observed that all the car buttons in car B, including the third floor car button 304, remain effective, so that a person at the 50 first floor may enter car B and have unrestricted use of the car, including being taken to the third floor if that is where such person desires to go. It is also to be observed that, under the conditions assumed, the car B hall buttons for each floor 55 other than the third remain effective so that immediate service may be provided by car B for an intending passenger at any of such floors other than the third while car A is destined to stop at the third floor.

It will be recalled that, for the above described operation, it was assumed that while car A was destined to stop at the third floor in response to a car button operation, the intending passenger at the third floor pushed both the third floor hall button 301 for car A and the third floor hall button 302 for car B. It is believed clear that if, instead, the intending passenger pushes only the third floor hall button 301 for car A, such operation of button 301 is likewise ineffectual, and that 70 if the intending passenger pushes only the third floor hall button 302 for car B, such operation of button 302 is likewise ineffectual.

Operation of car A in the down direction is 75 analogous to its previously described operations

in the up direction, except that, instead of up direction switch UA being actuated, down direction switch DA is actuated, and that the elevator motor and brake are controlled by contacts 45 and 47 of down direction switch DA instead of by contacts 44 and 46 of up direction switch UA. Whether the up or the down direction switch is actuated is determined by the positions of the floor selector switches 131, 230, 231, 330, 331 and 430, these being controlled by the position of car A. Thus, when the car is opposite an intermediate floor, both the up and the down selector switch for that floor have their contacts disengaged; when the car is below such intermediate floor the up selector switch contacts for that floor are in engagement and the down selector switch contacts for that floor are disengaged, and vice versa when the car is above such intermediate floor. Switches 230 and 231 are the up and the down selector switches, respectively, for the second floor; and switches 330 and 331 are the up and the down selector switches, respectively, for the third floor. Each terminal floor selector switch—switch 131 for the first floor and 430 for the fourth floor—has its contacts disengaged when the car is opposite the floor corresponding thereto, and in engagement at other times. Inasmuch as the stopping of the car at a floor is initiated by the separation of the contacts of the appropriate selector switch for such floor, it is understood that the separation of such contacts is effected shortly before the car arrives at such floor in order to provide a stopping zone at the termination of which the car, when stopping at such floor, has its platform level, or substantially level, with such floor.

It is unnecessary to describe operations of car A involving stops at floors other than the third, for such operations are similar to the operations described for the third floor. It is sufficient to note that floor relays 1FA, 2FA and 4FA for the first, second and fourth floors, respectively, correspond to floor relay 3FA for the third floor, that actuating coils 110, 210 and 410 correspond to actuating coil 310; that contacts 111, 211 and 411 correspond to contacts 311; and that contacts 112, 212 and 412 correspond to contacts 312.

Operation of car B in response to its car and hall buttons is similar to that for car A and is unnecessary to describe in detail other than to the extent already described. It is sufficient to note that the elements individual to car B having designating numerals from 57 to 97, inclusive, correspond respectively to elements individual to car A having designating numerals from 7 to 47, inclusive; that hatchway door interlock contacts 107, 207, 307 and 407 for car B correspond respectively to hatchway door interlock contacts 106, 206, 306 and 406 for car A; that selector switches 141, 240, 241, 340, 341 and 440 for car B correspond respectively to selector switches 131, 230, 231, 330, 331 and 430 for car A; that first-floor floor relay 1FB, its coil 120 and its contacts 121 and 122, for car B, correspond respectively to first-floor floor relay 1FA, its coil 110, and its contacts 111 and 112 for car A; that second-floor floor relay 2FB, its coil 220 and its contacts 221 and 222, for car B, correspond respectively to second-floor floor relay 2FA, its coil 210 and its contacts 211 and 212, for car A; that third-floor floor relay 3FB, its coil 320 and its contacts 321 and 322, for car B, correspond respectively to third-floor floor relay 3FA, its coil 310 and its contacts 311 and 312, for car A; and that fourth-floor floor relay

4FB, its coil 420 and its contacts 421 and 422, for car B, correspond respectively to fourth-floor floor relay 4FA, its coil 410 and its contacts 411 and 412, for car A.

Attention is directed to the fact that, although the invention has been illustrated in Figure 2 as applied to a group of two elevators each of the type commonly known as the single automatic push button elevator, with each elevator having hall buttons individual thereto, the invention is applicable to any group of two or more elevators in which each elevator is provided with a set of hall buttons individual thereto. Thus, the invention is applicable to a group of more than two elevators such as illustrated in Figure 2, and to a group of two or more single automatic push button elevators each having hall buttons individual thereto but without a movable car platform (as has each elevator in Figure 2), and with or without power operation of the car gate and/or hatchway doors, and with or without other variables, such as "in use" lights, "car coming" lights or position indicators. Also, the invention is applicable to a group of two or more elevators each having hall buttons individual thereto wherein interceptive or collective operation is provided by each car, in either or both directions of car travel, in response to the operation of the hall buttons for such car. The application of the invention to elevator installations of such character in which a single hall button is provided at each floor for each car, as shown in Figure 1, needs no explanation.

The application of the invention to elevator installations in which two hall buttons—an "up" button and a "down" button—are provided at each floor for each car, is illustrated in Figures 3 and 4. For simplicity, only two intermediate floors—the sixth and seventh—are considered, and only two cars—car G and car H. In addition, Figures 3 and 4 illustrate the application of the invention to an elevator installation employing floor relays of the latching type for registering demands for elevator service, together with car buttons in each car for use in registering floors to which passengers in such car desire to be taken.

Referring to Figure 3, at each of the two illustrated intermediate floors served by car G are provided two hall buttons for such car, hall buttons 601 and 611 being the up and down buttons, respectively, at the sixth floor for car G, and hall buttons 701 and 711 being the up and down buttons, respectively, at the seventh floor for car G. Similar hall buttons are provided for car H, hall buttons 602 and 612 being the up and down buttons, respectively, at the sixth floor for car H and hall buttons 702 and 712 being the up and down hall buttons, respectively, at the seventh floor for car H. Car buttons 603 and 703 in car G are for the sixth and seventh floors, respectively, and car buttons 604 and 704 in car H are for the sixth and seventh floors, respectively.

Each car is provided with a floor switch for each floor, each floor switch having a neutral position to which it is actuated when the car corresponding thereto is opposite the floor for which such floor switch is provided, having one operative position to which it is actuated when such car is above such floor, and having a second operative position to which it is actuated when such car is below such floor. Illustrative of such floor switches are the switches 660 and 760 for car G at the sixth and seventh floors, respec-

tively, these switches being actuated by an arm 502 mounted on car G. Similar floor switches 670 and 770 for car H are provided at the sixth and seventh floors, respectively, these switches being actuated by an arm 552 mounted on car H. Each floor switch is illustrated in the operative position thereof to which it is actuated when the car corresponding thereto is below the floor for which it is provided, since car G and car H are both illustrated as below the sixth floor. In such illustrated positions of the floor switches, the arms of floor switches 660, 760, 670 and 770 are in engagement with contacts 661, 761, 671 and 771, respectively (see Figure 4). In their other operative positions, the arms of floor switches 660, 760, 670 and 770 are in engagement with contacts 662, 762, 672 and 772, respectively.

It will be understood that instead of floor switches mounted in the hatchway, as illustrated, a selector machine, driven in synchronism with the car, may be provided with switches performing the same functions as the illustrated floor switches.

25 Referring now to Figure 4, the schematic diagram therein illustrated employs two latching floor relays per floor per car, one for the up direction and the other for the down direction. These floor relays are designated as follows:

- 30 6UG—Up floor relay, 6th floor, car G.
- 6DG—Down floor relay, 6th floor, car G.
- 7UG—Up floor relay, 7th floor, car G.
- 7DG—Down floor relay, 7th floor, car G.
- 35 6UH—Up floor relay, 6th floor, car H.
- 6DH—Down floor relay, 6th floor, car H.
- 7UH—Up floor relay, 7th floor, car H.
- 7DH—Down floor relay, 7th floor, car H.

It is to be understood that the illustrated construction of the latching floor relays is schematic in order to represent their manner of operation. Considering the details of one of such relays, for example, the sixth floor up latching floor relay for car G (up floor relay 6UG), such relay is provided with an operating coil 620 and a reset coil 621. Energization of operating coil 620 results in raising spindle 626 to effect the engagement of contacts 622 and 623 and the separation of contacts 624. The raising of spindle 626 also raises collar 627 secured thereto until, when spindle 626 is in its uppermost position, latch 628, under the influence of spring 629, cooperates with collar 627 to maintain the spindle in such uppermost position, and thus to maintain the relay in its operated position after operating coil 620 is deenergized. Energization of reset coil 621 withdraws latch 628 from collar 627, with the result that the relay spindle returns, by its own weight, to its initial position with contacts 622 and 623 disengaged and contacts 624 in engagement.

The other latching floor relays are similar to floor relay 6UG. Thus, operating coil 620, reset coil 621 and contacts 622, 623 and 624 of floor relay 6UG correspond respectively to: for floor relay 6DG, operating coil 630, reset coil 631 and contacts 632, 633 and 634; for floor relay 7UG, operating coil 720, reset coil 721 and contacts 722, 723 and 724; for floor relay 7DG, operating coil 730, reset coil 731, and contacts 732, 733 and 734; for floor relay 6UH, operating coil 640, reset coil 641, and contacts 642, 643 and 644; for floor relay 6DH, operating coil 650, reset coil 651, and contacts 652, 653 and 654; for floor relay 7UH, operating coil 740, reset coil 741, and contacts

742, 743 and 744; and for floor relay 7DH, operating coil 750, reset coil 751, and contacts 752, 753 and 754.

In the illustrated diagram the energization of the floor relay operating coils is subject to the hall buttons and to the car buttons to cause the floor relays to register demands for elevator service (or, as it may also be termed, to register desired passenger transfers). The energization of the floor relay reset coils is subject to suitable reset controls, these generally being effective as an incident to stops made at the floors. Schematically illustrative of a suitable reset control are the up selector contacts 625 and 725 adapted to be engaged by up selector brush 503 as car G, traveling in the up direction, nears the sixth and the seventh floors, respectively, and the down selector contacts 735 and 635 adapted to be engaged by down selector brush 504 as car G, traveling in the down direction, nears the seventh and the sixth floors, respectively. Selector brushes 503 and 504 are connected, through suitable switching mechanisms represented by square 505, to the plus main. When any floor relay is in operated position, the selector contact for the corresponding car, floor and direction of travel is rendered "alive" by being connected to the minus main through the reset coil for such floor relay. When such car, traveling in the appropriate direction, nears such floor, the selector brush corresponding to the direction of car travel engages the live selector contact, thereby completing a circuit for the reset coil for such floor relay and causing the resetting of such floor relay. Included in such circuit are the switching mechanisms 505 which, upon energization (assuming Figure 4 to represent schematically two elevators the slowing down and stopping of each of which is effected automatically), initiate the slowing down and stop of such car at such floor. It is unnecessary further to describe the switching mechanisms represented by 505.

For car H, selector contacts 645, 745, 755 and 655, selector brushes 553, 554, and switching mechanisms 555 correspond respectively to selector contacts 625, 725, 735 and 635, selector brushes 503, 504, and switching mechanisms 505, for car G.

Floor relay 6UG has been shown and described as being provided with contacts 623. These contacts, for convenience enclosed within a dot-and-dash rectangle 596 in which also are enclosed similar contacts 723, 733 and 633 of floor relays 7UG, 7DG and 6DG, respectively, are provided for those installations wherein the starting of the elevator car is subject to the control of registered demands for elevator service. It is unnecessary to describe their function in any further detail. In those installations in which the starting of the car is within the exclusive control of an attendant in the car, the contacts within rectangle 596 may be dispensed with.

The invention as applied to the system schematically represented in Figure 4 is best described by explaining its operation under different conditions. For simplicity, door operations are neglected. Assume first that cars G and H have been rendered available for service by closing knife switches 599, 501, 550 and 551, and that each car, when available for service, is subject to the control of its car and hall buttons automatically to effect starting of the car. Let it also be assumed that both car G and car H are below the sixth floor, as shown in Figure 75

3, that both cars are stationary, and that all time intervals, if any, have expired.

Under these conditions, let it be further assumed that an intending passenger at the sixth floor pushes up hall button 601 for car G. A circuit is thereby completed for operating coil 620 of floor relay 6UG, which circuit may be traced from the plus main, by way of knife switch 500, up hall button 601, contacts 644 of floor relay 6UH, operating coil 620, knife switch 501, to the minus main. Floor relay 6UG thereupon operates in the manner previously described to cause the engagement of contacts 622 and 623 and the separation of contacts 624, and floor relay 6UG is maintained in operated position after the release of push button 601. The engagement of contacts 622 renders "alive" up selector contact 625. The separation of contacts 624 will be referred to later. The engagement of contacts 623 causes the starting of car G in the up direction. When car G nears the sixth floor, up selector brush 503 engages up selector contact 625, thereby completing a circuit from the plus main, by way of knife switch 500, mechanisms 505, up selector brush 503, up selector contact 625, contacts 622 of floor relay 6UG, reset coil 621 of floor relay 6UG, knife switch 501, to the minus main. Floor relay 6UG is thereupon returned to its initial position, and at the same time the mechanisms 505 are actuated to initiate the stopping of the car so as to bring the car to a stop at the sixth floor. The intending passenger at the sixth floor may then enter car G and, upon indicating the floor to which he desires to be taken by pushing the car button corresponding to such floor, car G proceeds to take him to such floor.

Had the intending passenger at the sixth floor pushed up hall button 602 for car H instead of up hall button 601 for car G, car H would have responded to such call similarly as did car G. Thus, the engagement of up hall button 602 completes a circuit for operating coil 640 of floor relay 6UH, which circuit may be traced from the plus main, by way of knife switch 550, up hall button 602, contacts 624 of floor relay 6UG, operating coil 640, knife switch 551, to the minus main. The resulting operation of floor relay 6UH causes the engagement of contacts 642 and 643, and the separation of contacts 644. The separation of contacts 644 will be referred to later. The engagement of contacts 642 renders "alive" up selector contacts 645. The engagement of contacts 643 causes car H to start in the up direction. When car H nears the sixth floor, up selector brush 553 engages up selector contact 645, thereby completing a circuit from the plus main, by way of knife switch 550, mechanisms 555, up selector brush 553, up selector contact 645, contacts 642 of floor relay 6UH, reset coil 641 of floor relay 6UH, knife switch 551, to the minus main. Floor relay 6UH thereupon returns to its initial position and car H is caused to slow down and stop at the sixth floor. The intending passenger at the sixth floor can thereupon enter car H and be taken by it to the floor to which he desires to go.

In the event an intending passenger at the sixth floor pushes both up hall button 601 for car G and up hall button 602 for car H, it is observed that, in accordance with the invention, response is made thereto by only one car. Thus, assuming up hall button 601 for car G is pushed slightly prior to the operation of up hall button 602 for car H, the operation of such button for car G causes operation of floor relay 6UG and

response by car G to such demand for service in the manner previously described. Incident to the operation of floor relay 6UG is the separation of contacts 624. Contacts 624 are positioned in the circuit of the sixth floor up hall button for car H, with the result that while contacts 624 are separated, up hall button 602 for car H is ineffective to energize operating coil 640 of floor relay 6UH and thus, is ineffective to register a demand for service by car H, so that car H remains stationary. In the event up hall button 601 for car G is pushed slightly subsequent to the operation of up hall button 602 for car H, car H responds to such demand for service, and car G remains stationary, due to the separation of contacts 644 of floor relay 6UH. In the event up hall button 601 for car G and up hall button 602 for car H are pushed precisely simultaneously and maintained depressed, floor relays 6UG and 6UH flutter for an instant until one of them gets sufficiently out of step with the other to enable such one floor relay to attain operated position and be latched therein, which action thereupon renders ineffective the up hall button for the car corresponding to the other floor relay. In this latter instance response is made to the demand for service by only one car, similarly as in the preceding instances. It is clear, therefore, that when corresponding hall buttons at the same floor for cars G and H are operated, only one of such cars responds thereto.

Attention is directed to the fact that while the interconnection of the hall button circuits for cars G and H is such as to prevent more than one car responding to similar demands for service from the same floor, the arrangement is such that, with respect to the car buttons, the cars are independent so that both cars, whether going in the same or opposite directions, may stop at the same floor in response to the operation of the car button for such floor in the corresponding car. For example, assume that car G and car H are stationary at the first floor, and that a passenger at the first floor, desiring to go to the sixth floor, enters car G and pushes the sixth floor car button 603. A circuit is thereby completed for operating coil 620 of floor relay 6UG, this circuit being from the plus main, by way of knife switch 500, sixth floor car button 603, floor switch 660, floor switch contacts 661, operating coil 620, knife switch 501, to the minus main. The resultant operation of floor relay 6UG starts car G in the up direction and the car is stopped at the sixth floor, all in the manner previously described. While car G is traveling upwardly toward the sixth floor, assume further that another passenger at the first floor, desiring to go to the sixth floor, enters car H and pushes sixth floor car button 604. A circuit is thereby completed for energizing operating coil 640 of floor relay 6UH, this circuit being from the plus main, by way of knife switch 550, sixth floor car button 604, floor switch 670, floor switch contacts 671, operating coil 640, knife switch 551, to the minus main. The resultant operation of floor relay 6UH starts car H in the up direction and the car is stopped at the sixth floor, all in the manner previously described. It is to be observed that, due to the arrangement of circuits wherein contacts 624 of floor relay 6UG are positioned only in the circuit for up hall button 602, the separation of contacts 624 while car G is proceeding to the sixth floor does not prevent operation of floor relay 6UH by car button 604 in car H.

It is to be observed that the car button circuits and the hall button circuits are interconnected so

that while a car button stop is destined to be made by one car, the hall buttons at such floor for the other car or cars and for the direction in which the first car approaches such floor in response to such car button stop, are rendered ineffective. As a result, a second car cannot be caused to stop at a floor to provide service therefrom in a given direction when another car is already destined to provide such service. This may be illustrated by 10 assuming both car G and car H positioned below the sixth floor with car G traveling in the up direction and destined to stop at the sixth floor in response to an operation of the sixth floor car button 603. Under these circumstances, floor relay 15 6UG is in operated position with its contacts 624 separated. Assume further that an intending passenger at this floor, desiring to be taken to a floor above the sixth floor, pushes the sixth floor up hall button 602 for car H. Such operation of 20 push button 602 is ineffective to cause actuation of floor relay 6UH due to the separation of contacts 624. Car H therefore does not respond to such demand for service, service being provided by car G. In the event, under the above conditions, 25 it be assumed that the intending passenger at the sixth floor pushes the sixth floor up hall button 601 for car G instead of up hall button 602 for car H, such operation of hall button 601 energizes actuating coil 620 of floor relay 6UG, 30 but inasmuch as this floor relay is already in operated position, such energization is without further effect and service is still provided by car G. In the event, under the above conditions, it be assumed 35 that the intending passenger at the sixth floor pushes both up hall button 601 for car G and up hall button 602 for car H, it is clear that service is provided by car G and not by car H.

Further with respect to the interconnection of the car button circuits with the hall button circuits, 40 it is to be noted that the car button circuit for any floor for any car is interconnected with either the up or the down hall button circuits for the other car or cars for such floor, depending upon whether the car whose car buttons are under 45 consideration is below or above such floor, respectively. Thus, for example, the sixth floor car button 603 for car G is, when car G is below the sixth floor, interconnected with the sixth floor up hall button circuit for car H to render ineffective such up hall button and up hall button circuit upon 50 operation of the sixth floor car button 603 for car G. Such interconnection of car button 603 for car G does not extend, however, under the assumed conditions, to the sixth floor down hall 55 button circuit for car H, so that an intending passenger at the sixth floor, desiring to be taken to a floor below the sixth floor, may register, for car H, by operation of sixth floor down hall button 612 for car H, his demand for service.

In all the operations of the system of Figure 4 heretofore described, it has been assumed that the starting of each car is automatically effected in response to operation of car and hall buttons for such car. When the starting of such car is 60 within the control of an attendant in such car and the floor relay contacts within rectangles 506 and 556 are dispensed with so that the car and hall buttons for each car control only the stopping of such car, the heretofore described operations of Figure 4 are the same except that the starting of each car is effected by the attendant therein.

The invention is also applicable to elevator installations wherein both the starting and the stopping of each car are controlled by an att-

tendant therein, the invention in such instance being utilized with the signal equipment by which the attendants are informed of the stops to be made, and the mechanisms represented by squares 505 and 555 being mechanisms causing 5 an appropriate stopping signal to be given to the operator of the associated car in the manner well known in the art, instead of causing the actual stopping of the cars, as has previously been assumed.

Inasmuch as many changes could be made in the above constructions and many apparently widely different embodiments of this invention could be made without departing from the scope thereof, it is intended that all matter contained 15 in the above description or shown in the accompanying drawings shall be interpreted as illustrative and not in a limiting sense.

What is claimed is:

1. In an elevator installation having two or 20 more cars serving a floor and having a hall button at said floor individual to each of said cars, the combination with an actuating and stopping mechanism for each of said cars responsive to operation of the hall button at said floor corresponding to such car for causing such car, and such car only, to start toward said floor and stop thereat, of means responsive to the operation of the hall button for any one of said cars to render said mechanism for each of the other 30 of said cars unresponsive to its corresponding hall button.

2. A control system for two elevator cars each adapted to serve each of a plurality of floors, comprising; car actuating and stopping mechanism for each of said cars; two normally-open hall button switches at one of said floors, one for each of said cars; a floor relay for each of said hall button switches, each floor relay having a normally-open contact for controlling the car actuating and stopping mechanism for the corresponding car, and each floor relay also having a normally-closed contact; a circuit for each hall button switch and its floor relay by means of which the depression of the hall button switch 45 for either of the cars operates the floor relay for the corresponding car to close the normally-open contact and to open the normally-closed contact of such floor relay, said normally-closed contact of each floor relay being in said circuit for the other floor relay.

3. In combination; a plurality of elevator cars operable past a floor; a plurality of mechanisms, one for each of said cars, each of said mechanisms being individual to the car for which it is provided, and each comprising means, including a hall button at said floor and a car button for said floor within said car, for causing the corresponding car, and such car only, to stop at said floor in response to operation of either the hall button or the car button for said floor for such car; and means effective upon operation of either the hall button or the car button for said floor for one of said cars for rendering said mechanism for the other cars unresponsive to their corresponding hall buttons.

4. In combination; a plurality of elevator cars operable past a floor; a plurality of mechanisms, one for each of said cars, each of said mechanisms being individual to the car for which it is provided, and each comprising means, including a hall button at said floor and a car button for said floor within said car, for causing the corresponding car, and such car only, to stop at said floor in response to operation of either the 70

hall button or the car button for said floor for such car; and means effective upon operation of either the hall button or the car button for said floor for one of said cars for rendering said mechanism for the other cars unresponsive to their corresponding hall buttons at least until initiation of the stopping of said one car at said floor.

5. In an elevator installation; a floor; a plurality of elevator cars serving said floor; a plurality of hall buttons at said floor, one for each of said cars; a car button for said floor in each of said cars; means individual to each car, and responsive to operation of said hall button or said car button for such car, for registering, for such car only, demand for elevator service from and to said floor; and means operable upon registration of a demand for service by said car button in one of the cars for disabling said hall buttons for the other cars.

6. In combination, a plurality of elevator cars each serving the same floor; a plurality of hall buttons at said floor, one for each of said cars; a car button for said floor within each of said cars; car actuating and stopping mechanism for each of said cars; and means for each car responsive to the operation of the car button for said floor within such car, for causing the car actuating and stopping mechanism therefor to stop such car at said floor regardless of operations of said car buttons for said floor in others of said cars, and responsive to the operation of the hall button at said floor, for such car only, for causing the car actuating and stopping mechanism, for such car only, to stop such car at said floor only when no other of said hall buttons, and none of said car buttons, for said floor have been operated and are unresponded to.

7. In an elevator installation; a plurality of floors; two elevator cars each serving each of said floors; a floor relay for each of said cars for each of said floors, each of said floor relays having a set of normally-open contacts and a set of normally-closed contacts; car actuating and stopping mechanism for each of said cars, including the normally-open contacts of each of said floor relays for the corresponding car, responsive to the operation of any floor relay for the corresponding car to the exclusion of all other floor relays for the corresponding car, to maintain such floor relay operated, to start the corresponding car toward, and to stop such car at, the floor for which such floor relay is provided, and to restore such floor relay to its initial condition when such stop is made; a car button circuit for each of said floor relays for initially operating the respective floor relays from the respective cars, each car button circuit including a normally-open car button switch within the car and for the floor for which the corresponding floor relay is provided; and a hall button circuit for each of said floor relays for initially operating the respective floor relays from the respective floors,

each hall button circuit including a normally-open hall button switch at the floor and for the car for which the corresponding floor relay is provided, and also including the normally-closed contacts of the other floor relay for the same floor for which the corresponding floor relay is provided.

8. In an elevator installation having two or more cars serving a plurality of floors; a plurality of up hall buttons, one for each car, at each of said floors; a plurality of down hall buttons, one for each car, at each of said floors; a car button in each of said cars for each of said floors; means for each car responsive to the operation of any of said hall buttons or car buttons for that car for registering calls for that car; and means operable upon registration of a call by a car button in any one of said cars for any floor for rendering said up hall buttons for such floor for the other cars ineffective to register calls when said one car is below such floor at the time such car button is operated, and for rendering said down hall buttons for such floor for the other cars ineffective to register calls when said one car is above such floor at the time such car button is operated.

9. In an elevator installation having two or more cars serving a plurality of floors; a plurality of hall buttons, one for each car, at each of said floors; call registering means for each of said hall buttons, the call registering means for any floor for any car being responsive, under conditions where none of said cars are at the floor for which such call registering means is provided, to the hall button for which such call registering means is provided to register a demand for service for the car for which such call registering means is provided, regardless of the relative positions of the cars in their hatchways; and means responsive to the operation of call registering means for any floor for any car for rendering said call registering means for such floor for the other cars unresponsive to their respective hall buttons so long as such call registering means remains operated.

10. In an elevator installation having two or more cars serving a plurality of floors; a plurality of hall buttons, one for each car, at each of said floors; call registering means for each of said hall buttons, any one of said call registering means for any floor at which no car is positioned being responsive to the hall button for which such call registering means is provided to register a call for the car for which such hall button is provided, regardless of the relative positions of the cars in their hatchways, provided said call registering means for any of the other cars for such floor is not already operated; and means controlled by operated call registering means for any floor for any car for rendering said call registering means for such floor for the other cars unresponsive to their respective hall buttons.

HERMAN FREDERICK KRANTZ.
